UNITED STATES PATENT OFFICE

2,119,388

ELECTRIC SWITCH

Benjamin R. Hermann, Pittsfield, Mass., assignor
to General Electric Company, a corporation of
New York

Application October 6, 1933, Serial No. 692,414

15 Claims. (Cl. 200—114)

My invention relates to electric switches and more particularly to switches with fuses which are adapted to release the switch upon operation of the fuse.

In the protection of overhead outdoor transmission lines, it has become a common practice to combine a fuse with the line switch. For economy and safety it is desirable to locate the switch and the fuse combined with it near the top of the pole adjacent the transmission line. The opening and closing of the switch may be accomplished by a long switch stick with a hook adapted to engage the switch handle. However, examination of the fuse to determine whether or not it has operated and replacement of the fuse link is hazardous due to the close proximity of the live switch contact and transmission line. Combined switches and fuses have been provided with an arrangement for automatically opening the switch when the fuse operates. In this manner the operation of the fuse is clearly indicated without the necessity of a close examination. The automatic opening of the switch has the additional advantage of removing the voltage stress from the fuse holder after the operation of the fuse. While the fuse is intact there is no voltage stress on the fuse holder. When the fuse has completed its operation before the switch begins to open no arc is drawn between the switch and contact. On the other hand, if the switch does begin to open before the fuse has completed its operation, an arc may be drawn between the switch and contact which will do serious damage to the fuse holder and fuse support and may require its replacement.

An object of my invention is to provide an improved switch and combined fuse which will insure a completed operation of the fuse before the switch begins to open.

Another object of my invention is to provide a fuse holder which may easily be removed for the replacement of the fuse link and then replaced and reconnected in the circuit.

What I consider to be novel and my invention will be better understood by reference to the following specification and appended claims when considered in connection with the accompanying drawing in which Fig. 1 is a perspective view of a combined switch and fuse in operative position; Fig. 2 shows a portion of the fuse holder and switch contact with a switch stick engaging the handle to close the switch; Fig. 3 shows the fuse holder being removed for replacement of the fuse link; Fig. 4 shows the initial movement of the switch on operation of the fuse link; and

Fig. 5 is a perspective view on an enlarged scale of the switch handle.

Referring to the drawing, 10 indicates a cross arm secured to a pole, not shown, on which the transmission lines are carried. An insulator 11 is mounted on cross arm 10 by means of a strap 12 and two-part clamp 13. Strap 12 surrounds a reduced central portion of insulator 11 and is secured to one part of clamp 13. Strap 12 is held in close engagement with insulator 11 by bolt 14. The two parts of clamp 13 are pulled tightly against opposite sides of cross arm 10 which may vary in thickness by bolts 15. Upper switch contact 16 consists of a metal rod which extends about the upper end of insulator 11 and seats in an annular groove 17. The switch is guided to the contact surface of contact 16 by two flared ends 18 which form a V between them. Contact 16 is held in engagement with groove 17 by a combined clamp and connector 19. Contact 16 is clamped between two parts 20 and 21 of connector 19 by a stud 22. Stud 22 is provided with a longitudinal slot 23 in which a supply conductor 24 may be secured by a nut 25. Conductor 24 serves to connect contact 16 to one of the overhead transmission lines. Lower switch contact 26 is formed of a metal rod which surrounds the lower part of insulator 11 and seats in a groove 27. Contact 26 is held in position by a combined clamp and connector 28 which is similar to connector 19 previously described. The contact surface of contact 26 is in the form of a pivot pin on which switch 29 is pivoted. A load conductor 30 is connected to contact 26 by means of connector 28. The general construction of the switch and support is not my invention, but is the subject of another application Serial No. 692,469 filed concurrently herewith in the name of R. S. Bennett and assigned to the same assignee to which this application is assigned.

Switch 29 is provided with a fuse holder 31 consisting of a tube of insulating material in which a fuse link 31a is carried. The upper end of fuse holder 31 is closed by a contact cap 32. Cap 32 has a conical projection 33 which is adapted to be inserted between the two parts of contact 16. The shape of projection 33 is important because when it extends between the two parts of contact 16 it prevents the initial rotation of the fuse holder 31 to delay the opening of switch 29 upon the operation of the fuse to permit the extinction of the arc in a manner that will be described later.

Switch 29 is pivotally mounted on lower switch 26.

contact 26 by means of a toggle 34 and fuse holder support 35. Toggle 34 and support 35 are connected by a pivot pin 38. The fuse link 31^a located in fuse holder 31 is connected to toggle 34 by means of a thumb screw 37 and holds the toggle 34 in the closed position shown against the spring pressure of contact 16.

Toggle 34 is held with projection 33 in engagement with fuse support 35 when fuse link 31^a 10 is intact, fuse link 31^a being securely fastened at its opposite end to fuse holder 31. Thus a tension is transmitted through the fuse link 31^a to hold toggle 34 securely in position making switch 29 a single rigid structure which is adapted to pivot on lower switch contact 26. As long as fuse link 31^a is intact, switch 29 operates as an ordinary disconnect switch and may be opened and closed in the usual manner by pivoting it about lower switch contact 26. As switch 29 is closed, conical projection 33 of contact cap 32 passes between the two projecting ends 18 of contact 16 separating the two parts of contact 16 until projection 33 nests in the portion of contact 16 adjacent to projections 18 which form 25 the contact surface for the stationary switch contact. As switch 29 is closed, in addition to the above-described action of the projection 33 separating the parts of contact 16, it is also forced upwardly due to the vertical component of movement of the switch 29 in its rotation about lower switch contact 26. This produces a spring tension tending to force fuse holder 31 downwardly. Also, the separating of the two parts of upper switch contact 16 by the conical projection 33 30 produces a force tending to move the fuse holder 31 downwardly. However, as long as fuse link 31^a is intact, fuse holder 31 cannot move downwardly and rotational movement of fuse holder 31 is prevented by the abutting surfaces of contact 16 adjacent to the contact surface within 35 which projection 33 is seated.

Upon operation of the fuse link, the support for toggle 34 is removed and so it rotates about the eccentric pivotal connection between toggle 34 45 and fuse holder support 35, the movement of toggle 34 is not retarded by its connection to the support 35 and acts to vertically lower the fuse holder 31 as the toggle 34 swings open. Due to the 50 conical projection 33 on contact cap 32 extending between the contact cap and the switch 16 it prevents rotation of the fuse holder. The reaction to the expulsion of the high-pressure gases from the bottom of the fuse holder tube 55 31 prevents it dropping out immediately upon the operation of the fuse and following the action of toggle 34. Also, the projection 33 prolongs the time that the contact cap 32 is in engagement with switch contact 16 during vertical movement 60 of fuse holder 31. This time delay upon the automatic operation of the switch 29 is important as it permits the arc drawn on the operation of the fuse link to be completely extinguished within the fuse holder 31 before the switch opening 65 begins. Thus the arc is extinguished entirely within the fuse holder 31. If this time delay were not provided then a secondary arc would be drawn upon the separation of contact cap 32 from engagement with switch contact 16. This 70 arc would be more difficult to extinguish than the one located wholly within the fuse holder 31 and might result in serious damage to the fuse holder and fuse support. In Fig. 4 the position of fuse holder 31 is indicated shortly after the operation 75 of the fuse link with the fuse holder 31 having

moved longitudinally until the contact cap has separated from the switch contact 16. Longitudinal movement of fuse holder 31 is assisted by the pressure exerted by the two parts of contact 16 on conical projection 33 which is of particular importance when sleet or ice has formed on the switch contact 16. Fuse holder 31 then follows the movement of toggle 34 opening the switch 29 and assuming an angular position with the support 35 in engagement with projection 38 10 of toggle 34. Toggle 34 is stopped in its rotation about the pivot formed by switch contact 26 by engagement between projecting pins 39 of toggle 34 and side plates 40 secured to switch contact 26. The arrangement of the toggle 34 and fuse 15 holder support 35 is not my invention, but it is the subject of a copending application Serial No. 692,448 filed concurrently herewith in the names of C. J. B. Olsen and G. F. Lincks and assigned to the same assignee to which this application is 20 assigned.

For manual operation of the switch 29 and for removal of the fuse holder 31 to replace the fuse link located therein, a switch handle 41 is provided. Switch handle 41 is secured to fuse holder 25 31 adjacent the contact cap 32, the switch handle 41 being held in position on the fuse holder 31 by means of a screw 42. To prevent radio interference by static discharge between the metal switch handle 41 and contact cap 32, a small 30 copper wire spring 43 is provided engaging the switch handle 41 and contacting with the cap 32. An opening 44 is provided extending transversely of the switch handle through which the hook 45 of a switch stick 46 is adapted to pass. Switch 35 stick 46 is of the usual type used for opening and closing disconnecting switches and in Fig. 2 it is indicated in position for closing the switch 29. By pulling on the switch stick 46 the switch 29 would be opened. In Fig. 5 a detailed perspective view of switch handle 41 shows a strap 47 which extends between the two parts of the switch handle adjacent the upper part of opening 44. Strap 47 is provided for engagement with the hook 45 of switch stick 46 in the manner indicated in Fig. 3 for the removal of the fuse holder 31 when it is desired to replace the fuse link 31^a. It will be seen in Fig. 5 that the two parts of switch handle 41 are so formed as to fit the top 50 of switch stick 46 snugly so that the fuse holder 31 is securely held by switch stick 46 and may be easily removed from the switch contact 26 without the danger of the fuse holder 31 falling to the ground after it has been lifted from the contact 55 26.

From the foregoing it may be seen that the projection 33 retards the opening of the switch to permit the extinction of the arc within the fuse holder 29 before the switch begins its opening operation. In addition, the shape of projection 33 insures the opening of the switch upon the operation of the fuse regardless of whether or not the switch contacts are covered with sleet or ice. The switch handle 41 provides a means for the opening and closing of the switch 29 and the removal of the fuse holder 31 to replace the fuse link and make it possible for the linemen to perform these operations even at a distance of fifteen feet or more from the switch depending upon the length of the switch stick 46 at a relatively safe distance from any live parts of the switch. In addition the switch handle 41 makes it unnecessary to provide any special apparatus or equipment for performing these operations as the usual switch stick is all that is necessary. 70 75 75

- What I claim as new and desire to secure by Letters Patent of the United States, is:
1. An electric switch comprising stationary switch contacts, a fuse link, a fuse holder tube of insulating material, a contact cap mounted on one end of said tube and arranged to engage one of said switch contacts, means for pivotally supporting the fuse holder on another of said switch contacts, an operating handle secured to the fuse holder tube independently of and in spaced relation to said contact cap, and electrical conducting means interconnecting said operating handle and said contact cap to prevent static discharge therebetween.
  2. An electric switch comprising stationary switch contacts, a fuse link, a fuse holder tube, a contact cap closing one end of the fuse holder tube and having a projection adapted to engage one of said switch contacts, means to removably support and pivot the fuse holder on another of said switch contacts, an operating handle secured to the fuse holder and spaced from the contact cap, and spring means to connect the operating handle to the contact cap.
  3. An electric switch including in combination, supporting means, stationary switch contacts carried thereby, a fuse holder, means for removably and pivotally mounting said fuse holder on said supporting means for connection between said stationary contacts, and an operating handle secured to the fuse holder and constructed to provide for both manual operation of the switch and removal of the fuse holder from the supporting means by means of a switch stick having a hook member adjacent the end thereof and projecting substantially at right angles to the stick, said handle having socket means arranged to receive said hook member with the hook member disposed transversely of the longitudinal axis of the fuse holder and other socket means arranged to firmly engage the end of the switch stick and the hook member with the hook member disposed substantially parallel to the longitudinal axis of the fuse holder.
  4. An electric switch comprising supporting means, stationary switch contacts carried thereby, a fuse holder, means for removably and pivotally mounting the fuse holder on said supporting means for connection between said stationary contacts, and an operating handle secured to the fuse holder and having two parts disposed in spaced relation and provided with aligned openings for the reception of a hook member projecting from the end of an operating switch stick, said handle having also a strap member extending between said two parts and arranged to be engaged by said hook member when the end of said switch stick is inserted between said two parts.
  5. An electric switch comprising stationary switch contacts, a fuse holder, means to removably support and pivot the fuse holder on one of said switch contacts, and an operating handle secured to the fuse holder and having two parts with a transverse opening passing through the two parts, and a strap adjacent the opening connecting the two parts adapted for manual operation by a switch stick having a hook passing through the transverse opening and removed by a hook engaging the connecting strap.
  6. An electric switch comprising a switch contact having adjacent portions of a rod forming a contact surface, a second switch contact, a fuse holder, a contact secured to the fuse holder and having a conical projection adapted to pass be-

tween the two parts of said switch contact, means to support and pivot said fuse holder on said second switch contact, and means to release said fuse holder upon operation of the fuse whereby rotary movement of the fuse holder is opposed but longitudinal movement is permitted.

7. An electric switch comprising supporting means, a stationary switch contact mounted on said supporting means and having abutting surfaces resiliently biased toward each other, a second stationary switch contact, a fuse holder, a contact secured to said fuse holder and having a conical projection arranged to be engaged by the abutting surfaces of said first-mentioned stationary switch contact upon closing of the switch, means for supporting said fuse holder pivotally on said supporting means for connection between said stationary contacts, a fuse link located in said fuse holder, and means for releasing the support of said fuse holder upon the operation of the fuse link.

8. An electric switch comprising a stationary switch contact having abutting surfaces resiliently biased toward each other, a second switch contact, a fuse holder, a fuse link located in said fuse holder, means to pivotally support said fuse holder on said second switch contact, a contact secured to said fuse holder and having a conical projection passing between the abutting surfaces of said first-mentioned switch contact whereby rotary movement of the fuse holder is resisted but the pressures of said surfaces on said conical projection tends to effect longitudinal movement of the fuse holder.

9. In a disconnect switch, the combination with an insulating support and a movable connecting member pivotally mounted on said support, said member having a contact finger projecting axially from and tapered outwardly relative to the end of said member, of a contact comprising a pair of spaced resilient arms receiving said finger between them in frictional engagement therewith.

10. In a disconnect switch, the combination with an insulating support and a movable connecting member pivotally mounted on said support, said member having a contact finger projecting axially from and tapered outwardly relative to the end of said member, of a contact comprising a pair of spaced resilient arms receiving said finger between them in frictional engagement therewith, and latching means on said arms holding said finger against lateral movement but permitting endwise movement of said pin.

11. In a disconnect switch, the combination with an insulating support and a movable connecting member pivotally mounted on said support, said member having a contact finger projecting axially from and tapered outwardly relative to the end of said member, of a contact comprising a pair of spaced resilient arms receiving said finger between them in frictional engagement therewith, at least one of said arms having a portion converging toward the other for latching said member in frictional engagement with said arms.

12. In a disconnecting switch, the combination with an insulating support and a movable connecting member pivotally mounted on said support, said member having a tapered contact finger projecting from its end, of a contact comprising a pair of spaced resilient arms receiving said finger between them and in frictional engagement therewith, at least one of said arms

having a portion converging toward the other for latching said member in frictional engagement with said arms.

13. In a disconnect switch, the combination of an insulating support, a tubular fuse cartridge pivotally mounted at one end on said support, a contact carried by the support and comprising a pair of spaced substantially parallel resilient arms movable in a direction relatively towards the pivotal mounting of said tubular fuse cartridge, and a terminal cap closing the other end of said tubular fuse cartridge and having a tapered contact pin integral therewith and projecting therefrom to be received between said arms, said arms being in frictional engagement with the sides of said pin.

14. In a disconnect switch including a support, the combination with a fuse tube open at one end and closed at the other end by a cap having a tapered pin integrally therewith projecting concentrically relative to the tube, of a pivot carried by the support and upon which the open end of the tube is mounted, and a contact carried by said support and comprising a pair of wire prongs resiliently movable toward said pivot

and extending substantially relatively parallel, said prongs having converging portions disposed about said pin in frictional engagement with the sides thereof to latch the fuse tube in circuit closing position and said prongs being tensioned to exert pressure on said cap toward said pivot.

15. In a cutout switch, a pivotally mounted fuse tube open at one end and closed at the other by means of a metal cap having a tapered latch pin extending centrally therefrom, in combination with a terminal contact comprising a pair of spaced resilient members frictionally engaging the end of said cap and pressing thereon toward the open end of the tube, said members being provided with relatively converging latch portions engaging the latch pin to normally hold the tube against pivotal movement toward open circuit position and permitting manual movement of the tube to open circuit position, said fuse tube being movable bodily relative to its pivotal mounting, and means including a fuse link for controlling said means holding said tube against said bodily movement until the fuse link is severed.

BENJAMIN R. HERMANN. 26
